UNITED STATES PATENT OFFICE.

OREN R. CLINE, OF EL DORADO, KANSAS.

COMBINED TELEPHONE SIGNAL AND JACK.

SPECIFICATION forming part of Letters Patent No. 657,854, dated September 11, 1900.

Application filed February 6, 1900. Serial No. 4,211. (No model.)

To all whom it may concern:

Be it known that I, OREN R. CLINE, a citizen of the United States, residing at El Dorado, in the county of Butler and State of Kansas, 5 have invented a new and useful Combined Telephone Signal and Jack, of which the following is a specification.

This invention relates to signals in general, and more particularly to that class employed 10 in connection with the switchboard for telephones, one object of the invention being to provide a signal of simple and cheap construction and in which the act of inserting the plug will restore the signal.

15 A further object of the invention is to provide means in the path of movement of the visual member of the signal for closing a bell-circuit to attract attention.

In the drawings forming a portion of this 20 specification, and in which similar numerals of reference designate like and corresponding parts in the several views, Figure 1 is a sectional view of a portion of a switchboard and showing the parts of the present invention partly in section and partly in elevation, 25 the mechanism being in its set position. Fig. 2 is a view similar to Fig. 1, showing the positions of the parts after the electromagnet which operates the signal has been energized. Fig. 3 is a view similar to Fig. 1 and 30 illustrating the position of the plug after it has engaged the indicating element and moved it nearly to its set or restored position. Fig. 4 is an end view showing a modified 35 form of tube and a second form of indicator projecting therefrom.

Referring now to the drawings, 5 represents a portion of a switchboard having a plurality of similarly-equipped jack-sockets 40 in the usual manner, one of these openings being shown at 6 and formed with its front end of lesser diameter than the rear end. Within the opening 6 is disposed a tube 7, which is arranged with its forward end tilted 45 downwardly and terminating in the rear of the front face of the board 5. This tube 7 is adapted to receive an indicator element 8, which in the present instance is shown in the form of a ball, and which ball is of such a diameter as to move freely through the tube 7. The tendency of the ball is to roll downwardly and outwardly of the forward end of

the tube 7, that it may be visible by projecting from the forward end of the opening 6, and to hold the ball from total displacement 55 the contact-point of the line-spring 28, hereinafter described, is bent to be in the path of movement of the ball for engagement thereby. In order to hold the ball normally retracted to lie at the rear end of the tube 7, 60 an arc-shaped dog 10 is pivoted to an ear 11 upon the tube 7, one end of this dog being adapted to enter the tube through a slot 12 in the upper wall thereof. This inwardly-projecting end of the dog is adapted to lie 65 against the ball 8 and between it and the front of the board 5 to hold it securely in position, and in order to hold the dog in its operative relation to the ball a plate 14 is pivoted at one end to a suitable support and has 70 a lug 15 upon its face which is adapted to engage a notch 16 in the rear end of the dog 10. The position of this lug 15 is such that when engaged with the notch 16 the opposite end of the dog is projected inwardly of the 75 tube 7, as shown in Fig. 1 of the drawings.

The plate 14, above referred to, forms the armature of an electromagnet 17, to the frame 18 of which the armature is pivoted. The electromagnet 17 is disposed within an iron 80 casing 18 to increase its efficiency, and this casing extends beyond the front end of the electromagnet and forms a means for the attachment of the electromagnet to the rear face of the board 5 and in its operative position. Thus if the electromagnet 17 be energized the armature formed by the plate 18 will be attracted and will draw the lug 15 from the notch 16, when the dog 10 will be released and will fall to the position shown 90 in Fig. 2, and thus permit the ball 8 to roll downwardly and outwardly of the tube and project from the front of the switchboard. A spring-plate 20 is secured to the lower wall of the opening 6 and below the tube 7, the 95 free end of this plate extending forwardly beyond the end of the tube and into a position to receive the direct weight of the ball 8, when the plate will be depressed into contact with the contact-piece 22. The plate 20 and the contact-piece 22 are in the circuit of the battery 23, which includes also a bell 24, this circuit being adapted to be opened and closed also by a switch 25. Thus when desired the

switch 25 may be closed, so that the bell 24 will ring when the ball has rolled to the front of the board to perform its function of indication. A plug 27, of the usual form, is provided, and this plug is adapted to engage the ball 8 when in its indicating position and move it backwardly to be reengaged by the dog 10. A line-spring 28 is disposed in the upper portion of the opening 6 to normally engage a contact 29, which is connected directly in the circuit of the magnet 17, this spring 28 being adapted for engagement by the plug 27 for movement from the contact 29 to break the circuit of the magnet 17. 15 When the circuit of the magnet 17 is broken, the armature-plate 14 will move away from the electromagnet and will lie in a position to engage its lug 15 with the notch 16 and hold the ball retracted after the plug is withdrawn. 20 Above the spring 28 is a contact 30, which is connected with a ringing-generator in the ordinary manner and lies in the path of upward movement of the line-spring 28.

The plug 27 is of the usual construction, 25 having a cord (not shown) which is of the usual flexible wire. The end of the wire which is attached to the plug is electrically connected with a ring or collar 35 upon the outer surface of the plug, this collar having 30 a peripheral groove 36, which is so disposed that it will receive the angular lower end of the line-spring 28 when the plug has been moved into the tube 7 to an extent sufficient to engage the ball with the dog 10. When 35 the line-spring is in engagement with this groove 36, the plug-cord is in circuit with the line, and the line-spring is raised to lie in a position between and out of contact with the contact-points 29 and 30.

40 With the above construction it will be seen that when the electromagnet 17 is energized by the sending of a signal along the line-wire the ball 8 is released and rolls to project from the front of the board, it being understood 45 that the parts are normally in the positions shown in Fig. 1 of the drawings. After the ball has been released by the closing of the circuit of the electromagnet 17 the parts will lie in the positions shown in Fig. 2 of the 50 drawings. The plug 27 is then manipulated to press the ball 8 backwardly and is at the same time raised to make contact between the line-spring 28 and the contact 30 and is then dropped and moved on into the tube. This 55 momentary raising of the plug is sufficient to close the circuit between the line-spring and the contact 30 for a sufficient time to ring up, and when the plug has been moved all the way in the ball will lie in engagement with the dog 10, as illustrated in Fig. 1, and the 60 end of the line-spring will lie in engagement with the groove 36 to place the plug-cord in circuit with the line.

The structure of the present invention requires no act in returning the signals other than the mere insertion of the plug, the ball being positively returned and being retained

in a manner that will absolutely prevent accidental dislodgment, and consequently a false signal. When the mechanism of the present 70 invention is to be employed in connection with a complete metallic circuit, the usual and additional line-spring is used and a double plug is employed, all of which is well understood by those skilled in the art and needs no 75 illustration.

It will of course be understood that in practice a disk or ring may be substituted for the ball or that any bodily-movable object may be used and that various changes in the specific arrangement and construction shown may be made without departing from the spirit of the invention.

In Fig. 4 of the drawings is shown an end view of a modified form of tube which is rectangular in cross-section to receive a movable indicating-body in the form of a disk or ring 85 35. This tube is adapted to be placed in the same position as the tube 7 in Figs. 1, 2, and 3, and the central portions of the sides of the 90 tube are curved outwardly, as shown at 36, to receive the plug and permit movement of the indicating-body into engagement with its retaining-dog, which latter is constructed and equipped in the same manner as the dog 10. 95 In connection with this modified form of tube there is also employed the usual contact-springs for engagement by the plug and also is employed a spring for closing the circuit of the night-bell under the influence of the 100 weight or pressure of the disk or ring.

What is claimed is—

1. The combination with a switchboard having a jack-socket and an inclined guideway leading to the socket, a rotatable indicator 105 element in the guideway and adapted to roll therethrough into the jack-socket, a latch for holding the indicator element normally retracted, electrical terminals, and a plug having its body formed to enter the socket and 110 passage or guide way leading thereto, to move the indicator element into engagement with the latch and to engage a contact, said latch having electrically-operated means for releasing it from the indicator element. 115

2. The combination with a switchboard having a jack-socket, of a ball adapted for bodily movement to enter the socket, means for holding the ball normally retracted, means for releasing the ball to permit it to move to its 120 indicating position, a plug adapted to fit the socket and to engage the ball and move it to its retracted position, and electrical contacts disposed for engagement by the plug when the ball is moved into engagement with its 125 retaining means.

3. The combination with a switchboard having a jack-socket, of a guideway in the rear of the seat and leading thereto, a rotatable body disposed in the guideway and adapted 130 to roll through the guideway into the socket, a dog adapted to engage the body and hold it retracted, an electromagnet having an armature for operative engagement with the

dog to hold the latter in its operative position and to release the dog to release the body, a plug adapted to enter the socket and to engage the body and move it into engagement with the dog, and electrical contacts disposed for contact by the plug when the body is moved into engagement with its retaining means.

4. The combination with a switchboard having a jack-socket, of a tilted tube in the rear of the socket and leading thereto, a revolvable body disposed in the tube and adapted for movement therefrom into the socket, a dog adapted for engagement with the body to hold it in its retracted position, and an electromagnet provided with an armature adapted to engage and hold the dog operative and to release the dog to release the body.
5. The combination with a switchboard having a jack-socket adapted to receive a plug and a guide-tube leading thereto, of a rotatable indicator disposed in the tube for move-

ment therethrough into the socket, means for holding the body normally retracted, a signal-circuit including a movable circuit-closing terminal in the path of movement of the body to receive pressure thereof to close the circuit, and a plug adapted to enter the socket and engage the indicator and move it into engagement with its retaining means.

6. The combination with a switchboard having a jack-socket of a body adapted to roll into the socket, means for guiding the body to the socket, means for holding the body normally retracted, means for releasing the body to permit it to roll into the socket, and a plug adapted to enter the socket and engage the body and move it to its retracted position.

In testimony that I claim the foregoing as my own I have hereto affixed my signature in the presence of two witnesses.

OREN R. CLINE.
